UNITED STATES PATENT OFFICE.

ASHTON T. NELSON, OF WILTON JUNCTION, IOWA.

DESIGN FOR A MEMORIAL BUILDING.

Application filed August 12, 1927. Serial No. 23,072. Term of patent 7 years.

To all whom it may concern:

Be it known that I, ASHTON T. NELSON, a citizen of the United States of America, residing at Wilton Junction, in the county of Muscatine and State of Iowa, have invented a new, original, and ornamental Design for a Memorial Building, of which the following is a specification, reference being had to the accompanying drawings forming a part thereof.

I claim:

The ornamental design for a memorial building as shown.

ASHTON T. NELSON.
